DELAMAR C. BRIGGS, OF DETROIT, MICHIGAN, ASSIGNOR TO DETROIT STEEL PRODUCTS COMPANY, OF DETROIT, MICHIGAN, A CORPORATION OF MICHIGAN.

AUTOMATIC LOCK FOR METALLIC WINDOWS.

1,125,951.

Specification of Letters Patent.

Patented Jan. 26, 1915.

Application filed April 24, 1913. Serial No. 763,368.

To all whom it may concern:

Be it known that I, DELAMAR C. BRIGGS, a citizen of the United States of America, residing at Detroit, in the county of Wayne and State of Michigan, have invented certain new and useful Improvements in Automatic Locks for Metallic Windows, of which the following is a specification, reference being had therein to the accompanying drawings.

The invention relates to metallic window construction in which ventilation is provided through swinging sash sections.

The object of the invention is to provide a simple construction of automatically latching lock, which permits the closing of the swinging sash and securely locks the same when closed.

In the drawings: Figure 1 is a front elevation of the lock, showing a fragment of the window sash to which it is applied; Fig. 2 is a side elevation thereof; Fig. 3 is a horizontal section, showing the lock in plan; and Figs. 4 and 5 are respectively diagrammatic front and side elevations, showing a stationary sash and ventilator with the locking mechanism applied thereto.

A is the stationary portion of a metallic window sash and B is the swinging sash or ventilator secured therein by suitable pivots (not shown).

C is a notched brace bar or stay for holding the ventilator section in open position, being pivotally secured to the latter at D by ear plates E secured to one of the sash bars F.

The automatic lock comprises a lever G, which is pivotally secured to the swinging or ventilator section so as to be movable in a plane parallel to the plane of the swinging sash. This lever is preferably pivoted to the sash by being secured between angle plates H and H', which are secured upon opposite sides of the web portion of the bar F so that their angle flanges are parallel to each other and to the plane of the sash.

I is the pivot pin or bolt for securing the lever between the angle plates H and H'.

The lever G is preferably formed with a portion J normally projecting vertically downward from the pivot and terminating in a laterally-extending tapering nose portion K inclined to both the vertical and horizontal planes. Above the pivot the lever G is preferably offset or bent outward at

L to give clearance from the sash, and then extends at right angles or parallel to the plane of the sash to form an operating and gravity-actuated arm M. The construction is such that the inclined and tapering nose 60 portion K of the lever swings in a path which is intercepted by the upper rail N of the stationary sash section, against which the lower rail O of the swinging sash section abuts to form a weather stop. The nose 65 K is, however, so fashioned that upon contacting with the stop rail N it will ride over the same, turning the lever upon the pivot I and lifting the gravity arm M. This will turn the portion J of the lever upward so 70 as to clear the upper edge of the bar N, upon passing which the weight of the arm M will return the lever, moving the portion J downward adjacent to the inner face of the bar N. The portion J is preferably 75 slightly inclined or wedge-shaped, so that in moving downward it not only engages the bar N to prevent outward movement of the sash, but also has a wedging or drawing effect for tightening the lower rail O of the 80 swinging sash against said stop rail N.

One advantage of the construction, as described, is that the lever G extends and is swung in a plane parallel to the sash, which permits of a suitable length of lever without projecting the same any considerable distance beyond the plane of the sash. Another advantage is that the latch, when it automatically engages to lock the sash, also has a wedging or drawing effect for tightly 90 closing the same.

What I claim as my invention is:

1. The combination with a swinging window sash, of a stop for said sash, a gravity-actuated arm pivotally secured to said sash 95 to swing in a plane parallel thereto, provided with a portion for lifting said lever in passing said stop and a portion for wedging engagement with said stop when past the latter.

2. The combination with a swinging window sash and a stop for said sash, of an automatically latching lever secured to said sash to swing in a plane parallel thereto and adapted to automatically clear said stop in 105 passing the same and to have a wedging engagement with said stop when past the latter.

3. The combination with a swinging window sash and a stop for said sash, of an au- 110

tomatically latching lever secured to said sash, said lever having a downwardly extending portion extending into the path of said stop during the closing movement of the sash and parallel to said stop in closed position, and being slightly tapered for a wedging engagement with said stop when past the latter, said lever having a portion offset outwardly to give clearance from the sash and an arm portion extending substantially parallel to the plane of the sash.

4. The combination with a swinging window sash and a stop for said sash, of an automatically latching lever secured to said

sash to swing in a plane substantially parallel thereto and adapted to automatically clear said stop in passing same, said lever having one end slightly tapered for a wedging engagement with said stop and its opposite end offset outwardly and extending substantially parallel with the sash. 15

In testimony whereof I affix my signature in presence of two witnesses.

DELAMAR C. BRIGGS.
